UNITED STATES PATENT OFFICE.

GEORGE C. EDWARDS AND BURNETT V. BUFFINGTON, OF MARYSVILLE,
OHIO.

CASTING FOR ROPE HALTERS.

SPECIFICATION forming part of Letters Patent No. 465,777, dated December 22, 1891.

Application filed April 18, 1891. Serial No. 389,522. (No model.)

To all whom it may concern:

Be it known that we, GEORGE C. EDWARDS and BURNETT V. BUFFINGTON, both of Marysville, Union county, Ohio, have invented 5 a new and Improved Casting for Rope Halters, of which the following is a specification.

This invention relates generally to halters, and more particularly to an improved casting-piece to which a single piece of rope is 10 attached to produce the throat-latch and nose-strap, the free end of the rope forming the hitching-strap, the object of the invention being to provide a cheap and simple casting, which is so constructed and arranged 15 that it will not annoy the animal, and it is also constructed in such form that the manner of using it will be readily perceived.

With these objects in view our invention consists in the peculiar construction of the 20 parts and the novel combination or arrangement of the same, all of which will be fully hereinafter described and claimed.

In the drawings forming a part of this specification, Figure 1 is a perspective view 25 of our improved halter as applied and used. Fig. 2 is a perspective view of the halter.

In the practical embodiment of our invention we employ a casting A, comprising a main or body portion a, which body portion 30 is provided at its forward end with oppositely-projecting lateral arms a', thus forming a T-shaped forward portion. Near the forward end of the body portion a is produced an aperture a², and near the outer ends 35 of the arms a' are produced the apertures a³, the arms and body portion being preferably enlarged where the apertures are produced to prevent weakening the casting. The rear end of the main or body portion a is provided 40 with rearwardly-projecting oblique arms a⁴, forming a forked or Y-shaped rear end of the casting, and near the rear end of the body portion is also produced an aperture a⁵, while near the ends of the oblique arms are produced the apertures a⁶. A rope B is passed 45 through the several apertures and around the various arms, producing the throat-latch b, the nose-strap b', and the hitching-strap b², the free end of the throat-latch being provided 50 with a snap-hook b³. In attaching the rope to the casting the end of the rope is passed through one of the apertures a⁶ in the rear arm a⁴ from the upper side and drawn

through a sufficient distance to leave enough remaining to form the throat-latch b, the 55 snap-hook being adapted to engage the opposite aperture a⁶ after said rope has been passed around an animal's head. The end of the rope after being passed through the aperture a⁶ is passed up through the aperture a⁵ 60 in the rear end of the body portion, and is then passed down through the aperture a² at the forward end of the body a and up through the aperture a³ in the arm a' adjacent to the arm a⁴, through which the rope was first 65 passed. The rope is then carried across to the opposite aperture a³, forming the nose-strap b', and it is then passed up through the aperture a² and beneath the rope as it passes down through said aperture. The rope is 70 then carried over the forward end of the body portion, and up again through the aperture a², and out through the loop b⁴, formed at the forward end of the body, thus producing a knot, which retains the rope in its proper 75 place of arrangement with the casting. If desired, the rope may be passed through in the reverse order, but preserving the same arrangement. The forward arms a' are preferably curved upwardly, thereby forming a 80 support for the nose-strap.

Although we have spoken of the part A as a casting, and prefer to make the same of cast metal, it is evident that it may be made of wrought metal or struck up from thick 85 sheet metal, the peculiar construction of the piece and the arrangement of the rope thereon being the essential features whereby an adjustable halter of cheap and simple construction is provided.

Having thus described our invention, what we claim, and desire to secure by Letters Patent, is—

An improved casting for halters, consisting of main or body portion, having apertures 95 near its forward and rear ends, the laterally-projecting and upwardly-curved forward arms having apertures near their outer ends, and the obliquely-projecting rear arms having apertures near their outer ends, substantially as and for the purposes described.

GEORGE C. EDWARDS.

BURNETT V. BUFFINGTON.
